UNITED STATES PATENT OFFICE.

JOSEPH A. NEAL, OF MOBILE, ALABAMA, ASSIGNOR TO JOHN C. HASWELL, OF DAYTON, OHIO, HARRY STOVER, OF MOBILE, ALABAMA, AND JOSEPH A. NEAL, OF CRICHTON, ALABAMA, TRUSTEES.

SEPARATING DEVICE FOR SAWING MACHINES.

Original application filed December 17, 1919, Serial No. 345,518. Divided and this application filed August 23, 1920. Serial No. 405,333.

To all whom it may concern:

Be it known that I, JOSEPH A. NEAL, a citizen of the United States, residing at Mobile, in the county of Mobile and State of Alabama, have invented certain new and useful Improvements in Separating Devices for Sawing Machines; and I do hereby declare the following to be a full, clear, and exact description of the invention, such as will enable others skilled in the art to which it applies to make and use the same.

This invention relates to re-sawing machines, and has for its object to provide a simple, efficient and inexpensive device for yieldingly holding apart the pieces of stock separated by the saws so as to keep the kerf open and prevent binding action of the stock upon the saws, together with means for supporting and guiding the material as it is passed through the machine and means for holding the material down in proper position for the action of the saws with a yielding and variable pressure.

The invention will first be hereinafter more particularly described, with reference to the accompanying drawings, which form a part of this specification, and then pointed out in the claims at the end of the description.

In said drawings:

Fig. 1 is a plan view of a re-sawing machine embodying my invention;

Fig. 2 is a side elevation of the same, the lower portion thereof being broken away;

Fig. 3 is a sectional side elevation of a fragmentary portion of the machine taken on a line between the two guide bars, the superposed hold-down device being removed;

Fig. 4 is an end view of the separator housing or casing; and

Fig. 5 is a plan view of the yielding separator or kerf opener.

Referring to said drawings, in which the same reference letters are used to denote corresponding parts in different views, the letter A may denote the machine frame, which may be of the form shown, or any ordinary construction, and to which may be secured laterally and vertically adjustable mandrel-supporting frames B, carrying circular saws C. Said frames B are preferably, of sub-

stantially the same construction as the mandrel-supporting frames shown in my Patent No. 1,340,286 dated May 18, 1920, but any suitable form may be employed. On the frame A are mounted a pair of guide bars D, D, between which the material or stock to be operated on by the saws is guided and held in proper position for the action of the saws as it passes through the machine. The bars D, D, are each formed or provided on the outer side thereof at or near each end with laterally projecting base flanges d, d, which have oblong slots therein to receive fastening bolts or screws d¹, d¹ for securing said flanges to the supporting frame so as to permit lateral adjustment of either or both guide bars to adapt them to receive therebetween stock of different widths. The front ends of the guide bars D, D, are each slightly bent or turned outwardly, as at d², d², to widen the space for the entrance of the material between said guides. Between the guide bars D is secured a bed-plate E of sufficient length to properly support the material in its passage between the guide bars D. To accommodate stock of different thicknesses, the bed-plate E is supported by means of front and rear screws e, and an intermediate set screw e¹, on which it rests, the screws e, being swiveled thereto and screwed into threaded openings therefor in the frame-bar a, and the intermediate screw or screws e¹ are also screwed into threaded openings in said frame-bar a, thus adapting the bed-plate to be adjusted or raised and lowered and held at different heights. The guide bars D are slotted longitudinally intermediate their length to permit separating disks F, F, to protrude therethrough, as shown, and are formed or provided on their upper outer sides or margins near their front ends with laterally projecting lugs d³, d³, having oblong slots or holes 95 therein to receive set screws or bolts d⁴, d⁴, for securing thereto a superposed supporting member or housing X, for a hold down or presser-foot device such as shown in my pending application, Serial No. 345,518 filed December 17, 1919 (now Patent No. 1,356,110 dated October 19, 1920), of which this application is a division.

Rotary separating devices or disks F,

each journaled at the inner end of a longitudinally movable rod G, protrude through the side slots in the guide bars D, D, in position to enter the cut made by the saws and hold the cut pieces apart. The rods G are each slidably fitted and housed within a casing H, attached to the outer side of the guide bar D, said housing being preferably of tubular form and having on the inner 10 end thereof a flat faced plate h, extending at an angle thereto and provided with open-ended slots h¹ on opposite sides (Fig. 4) to receive set screws or bolts for securing it to the outer side of the guide bar, as shown in Figs. 1 and 2. In order that the disk may be held in proper position to enter the kerf or cut made by the saws, a stud or pin g on the rod G protrudes through an oblong slot h² in the housing H, parallel 20 with the axis of the disk, to prevent the rod from rotating while permitting movement thereof in the direction of its length. The free end of the rod G passes through an aperture in the outer end of the housing 25 H, which forms an abutment for one end of a spring I, placed on the rod G between said abutment and a nut i screwed on the rod, so that the spring will yieldingly force the rod toward the fixed end of the housing 30 and thereby force the disk into the kerf made by the saws. A nut i¹ screwed on the free end of the rod G, beyond the outer end of the housing, is adapted to contact with said end and thereby limit the inward movement of the rod beyond a predetermined point. By adjusting the nuts i and i¹ the tension of the spring may be varied to adapt it to exert greater or less pressure 35 as desired.

40 The housing X has journaled therein a pair of eccentric pins or cam shafts which are provided with operating handles x and on which are pivotally mounted presser-feet x¹ having their lower ends arranged to bear upon the material or stock and hold it down upon the supporting bar or bed-plate E with a yielding pressure, which is exerted by spring-actuated rods x², the lower ends of which are pivoted to the upper ends of 45 said presser feet so as to exert a force tending to lift the upper ends of the presser-feet and force the lower free ends thereof down upon the stock. This hold-down device, however, is not specifically claimed 50 herein as it forms the subject matter of my aforesaid application, Serial No. 345,518, and need not be further described.

55 It will be observed that the separating devices F are so inclined in relation to the guide bars that they will readily yield to any excess pressure exerted by the stock tending to force them back into their housings against the pressure of the springs acting thereon and when such excess pressure is removed, the springs will immedi-

ately restore the separators to normal position.

While I have shown and preferably employ a pair of separating devices, one arranged on each side of the material operated on by the saws, and a pair of hold down devices or presser-feet together with a supporting bar or bed-plate on which the material slides as it is advanced toward the saws, it may be desirable in some cases to use a single separator or a single hold down device or presser-foot, and various other changes may be made in the details of construction and arrangement of parts without departing from the spirit and scope of my invention, and I therefore do not desire to be limited to the exact construction or arrangement shown and described.

Having thus described my invention, what I claim as new and desire to secure by Letters Patent is:

1. In a sawing machine, means for yieldingly holding apart or in separated relation the two pieces of material acted on by the saws, comprising a disk journaled at one end of a rod extending at an angle intersecting the path of movement of the material through the machine, a spring adapted to yieldingly force the disk into the kerf, and means to prevent rotary movement of said rod while permitting movement thereof in the direction of its length.

2. A yieldable separating device of the character described, comprising a tubular housing having at one end a plate extending at an angle thereto and adapted for attachment to a guide bar extending longitudinally of the machine frame, said guide bar having an elongated slot therein, a longitudinally movable rod within said housing carrying at one end a disk protruding through said slot and having the other end thereof protruding through the outer end of said housing, a spring adapted to yieldingly force the rod toward the fixed end of the housing, and means to prevent rotary movement of the rod while permitting movement thereof in the direction of its length.

3. In combination with spaced guide bars extending longitudinally of the machine frame, means for yieldingly holding apart or in separated relation the two pieces of material acted on by the saws, comprising a disk protruding through one of said bars, said disk being revolvably mounted on a longitudinally slidabie rod extending at an angle intersecting the path of movement of the material through the machine, a spring acting on said rod to yieldably force the disk into the kerf, and means to prevent rotary movement of said rod while permitting movement thereof in the direction of its length.

4. The combination, in a sawing machine,

of means for supporting and guiding through the machine material of different thicknesses and widths to be acted upon by the saws, together with means for separating and holding apart the pieces cut by the saws; said supporting and guiding means comprising a pair of laterally adjustable guide-bars having oblong slots therein near their delivery ends and a vertically adjustable supporting bar arranged between said guide-bars at their receiving ends, and said separating and holding means comprising knife-edged devices protruding through the slots in said guide-bars and secured to spring-pressed rods slidably fitted in supporting members which project from said guide-bars at an angle to the path of movement of the material through the machine.

5. In a sawing machine, the combination with means for supporting and guiding material through the machine in position to be acted upon by the saws including a pair of guide-bars having oblong slots therein near their delivery ends, of means for separating and holding apart the pieces cut by the saws, the latter means comprising knife-edged devices protruding through said slots and adapted to enter the kerf on opposite sides of the material, springs for yieldingly forcing said separating devices into the kerf, and means for varying the tension of said springs.

6. In a sawing machine, a yieldable kerf opener comprising a pair of rods arranged at an angle to the path of movement of the material through the machine, said rods carrying separating devices which protrude through guide-bars between which the material moves, springs on said rods for yieldingly forcing the separating devices into the

kerf, and means for varying the tension of said springs.

7. The combination, in a sawing machine, of guide-bars between which the material passes through the machine, and means for separating the pieces of material cut by the saws, said means comprising a hollow housing member having at one end a flat-faced plate extending at an angle thereto, means for securing said plate to the outer side of one of said guide-bars, a rod slidably fitted in said housing member, said rod carrying a separating device at its inner end which protrudes through an opening or slot in the guide-bar into position to enter the kerf, a nut screwed on said rod within said housing member, a spring placed between said nut and the inner wall of said housing member and tending to force said rod toward the guide-bar, and a nut screwed on said rod for adjusting the tension of said spring.

8. The combination, in a sawing machine, of means for supporting and guiding through the machine material to be acted on by the saws, said means comprising a pair of guide-bars having oblong slots therein, and yieldable means protruding through said slots for separating and holding apart the pieces cut by the saws, said yieldable means comprising spring-pressed rods slidably fitted in supporting members secured to said side bars at an angle to the path of movement of the material through the machine.

In testimony whereof I affix my signature in the presence of two witnesses.

JOSEPH A. NEAL.
